(57) **CLAIM**

The ornamental design for baseball wheel cover, as shown and described.

DESCRIPTION

FIG. 1 is an isometric view of a baseball wheel cover in accordance with an embodiment of the present invention.

FIG. 2 is a front view thereof;

FIG. 3 is a left-side view thereof;

FIG. 4 is a right-side view thereof;

FIG. 5 is a top view thereof;

FIG. 6 is a bottom view thereof;

FIG. 7 is a back view thereof; and,

FIG. 8 is a side view of the baseball wheel cover of FIG. 1, illustrating its mounting position on a wheel drawn in phantom.

The broken line showing of environment is for illustrative purposes only and forms no part of the claimed design.
